UNITED STATES PATENT OFFICE.

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS.

THREAD CLAMPING AND SHEARING MEANS.

Application filed May 7, 1923. Serial No. 637,049.

To all whom it may concern:

Be it known that I, HOWARD D. COLMAN, a citizen of the United States, residing at Rockford, in the county of Winnebago and State of Illinois, have invented a certain new and useful Thread Clamping and Shearing Means, of which the following is a specification.

This invention relates to thread clamps, and more particularly to a clamp of such character that when the thread is drawn into the clamp the thread will be automatically clamped and severed.

The invention has special, although not exclusive, reference to means for holding the end of the thread of a reserve bobbin in an automatic winder of some such type as that disclosed in the Colman Patent No. 1,267,977 dated May 28, 1918. In the operation of the machine shown in the Colman Patent, the operative finds the end of the thread on a reserve bobbin, places the bobbin in the bobbin holder, and draws the thread into the spring clamp shown in Fig. 57 of the patent.

25 The portion of the thread held in the hand of the operative and extending to the clamp is then broken off and discarded. In the operation of breaking off the surplus thread-portion, the thread sometimes parts at such a point that it escapes from the thread clamp, with the result that the thread of the reserve bobbin is not held in position for operation thereon by the traveling winder-tending mechanism. At other times, the 30 surplus thread-portion is not broken off close enough to the thread clamp, thus leaving an objectionably long thread to be disposed of by the winder-tending mechanism.

35 The object of the present invention is to provide means for clamping the reserve thread and trimming it to a predetermined length by means which shall be automatically actuated in the single act of drawing the thread into the clamp.

40 In the accompanying drawings, Figure 1 is a fragmental view of a winder showing how a thread-clamp embodying the present invention is related to the bobbin-holder. Fig. 2 is a fragmental plan view upon a larger scale than that employed in Fig. 1. Fig. 3 is a rear view of the thread clamp, that is to say, a view taken from the left-hand side of Fig. 1. Fig. 4 is a front elevation of the parts shown in Fig. 1. Fig. 5 is a plan view of the thread clamp with

the cover removed. In this view, the thread clamp is shown open. Fig. 6 is a vertical sectional view taken in the plane of line 6—6 of Fig. 5. Fig. 7 is a vertical section on line 7—7 of Fig. 5. Fig. 8 is a view taken in the plane of line 8—8 of Fig. 5. Fig. 9 is a view similar to Fig. 5 but showing the clamp closed. Fig. 10 is a fragmental perspective view of the shearing and clamping means, per se. Fig. 11 is a view taken in the planes of line 11—11 of Fig. 5.

Referring to Figs. 1 and 4, A is the bobbin-holder, and B is the thread clamp, considered as a whole. The thread clamp B is attached to a bracket C by means of a bracket 1 (Fig. 11). The bracket 1 comprises a vertical web 2 which is secured to the bracket C by means of a screw D extending through an opening 3. The bracket 1 further comprises a horizontal web 4 which is welded or otherwise rigidly secured to the thread clamp housing. Integral with the bracket 1 is a thread-guiding finger 5.

The thread clamp proper is enclosed within a housing consisting of a main section 6 and a cover 7 (Fig. 11). The main section 6 comprises a bottom wall 8 and two parallel flanges 9 and 10. The cover 7 has a hook 11 adapted to enter an opening 12 in the flange 10; and the flange 13 is adapted to be sprung over the flange 9.

The means for clamping and shearing the thread comprises a clamping jaw 14 (Fig. 10) having a stem 14^a, a shearing blade 15, and an intermediate pivoted clamping and shearing jaw 16. The clamping and shearing means is held in proper position within the housing 6 by means including a spring clip 17 (Figs. 7, 10 and 11) which is formed integral with the stem 14^a, and is adapted to frictionally engage the bottom wall 8 of the housing and the lower face of the bracket portion 4. The lower wall 8 is notched, as shown at 18, to accommodate the clip. On the stem 14^a is an upwardly extending lug 17^a which engages the cover 7, whereby said cover serves to hold the shearing and clamping mechanism against upward displacement.

105 The clamping and shearing jaw 16 is connected to the clamping jaw 14 by means of a rivet 19 (Fig. 11) which extends through the jaw 14 and a bushing 20, said rivet serving to secure the bushing to the 110

jaw 14. The head of the rivet 19 lies within an opening 21 in the bottom wall of the housing.

The shearing blade 15 is formed of resilient material and is detachably secured in proper relation to the jaws 14 and 16 by means including a clip or holder 22 formed integral with the upper branch of the clip 17. In the shearing blade 15 is an opening 23 through which the bushing 20 extends. The shearing blade 15 has a stem 24 adapted to be sprung into the clip 22.

As best shown in Fig. 10, the coacting edges of the jaws 14 and 16 are sufficiently dull so as to clamp the thread between them, whereas the coacting edges of the jaws 15 and 16 are sharp enough to shear the thread. As indicated in Fig. 8, the coacting edges of the three blades are so arranged with relation to one another that the thread is clamped before it is severed. As will be understood from Figs. 7 and 8, the spring blade 15 furnishes the pressure necessary to clamp the thread between the jaws 14 and 16.

The means for swinging the clamping and shearing jaw 16 comprises, in this instance, a three-arm lever 25, a gear segment 26 fixed with relation to the lever 25, and a gear segment 27 formed integral with the jaw 16. In the construction herein shown, the lever 25 and the segment 26 are formed from an integral piece of sheet metal, said lever comprising an arm 28 arranged to be engaged by a thread, an arm 29 arranged to be operated by an element E (Fig. 2) on the travelling winder-tending mechanism, and a double arm 30. The lever 25 and the segment 26 are pivoted upon a stud 31 which is riveted to the bottom wall 8 of the housing and which extends through an opening in a depressed portion of the cover 7 (see Figs. 2 and 6). One end of a link 32 is pivoted upon a rivet 33 carried by the arm 30. The link 32 extends past the pivot 31 and is connected at its other end to a helically-coiled contractile spring 34 which is anchored to a lug 35 rising from the clip 17.

The arm 29 projects through a notch 36 in the wall 9 of the housing. The cover 13 is cut away, as shown in Fig. 4, to accommodate the arm 29. The opposite end walls of the notch 36 serve to limit movement of the clamping and shearing jaw 16. By reference to Fig. 5, it will be seen that when the clamp is open, the center 33 is slightly at one side of a straight line passing through the pivot 31 and the anchorage for the spring 34; consequently said spring serves to hold the clamp in open position.

One end of the bottom wall 8 and the corresponding end of the cover 7 are shaped to provide, in conjunction with the guide 5, a flaring throatway or entrance 37 (Figs. 2 and 5) leading to a slot 38 which extends alongside the jaws 14 and 15 (see Figs. 5

and 8). When the clamp is open, the shearing and clamping jaw 16 extends across the slot 38 as shown in Fig. 5. So also does the arm 28, said arm consequently being in the path of a thread which is being drawn into the slot 38.

Assuming the clamp to be open, as shown in Fig. 5, the operation is as follows: The operative takes a bobbin in her left hand, finds the end of the thread on the bobbin, drops the bobbin into the bobbin-holder, and draws the thread through the throatway 37 and into the slot 38.

The pressure of the thread against the arm 28 is sufficient to move the arm until the pivot 33 has passed over center, whereupon the spring 34 throws the three-arm lever 28 into the position shown in Fig. 9, whereby the jaw 16 is swung against the thread, and the thread is clamped and severed as illustrated in Fig. 10. The thread of the reserve bobbin is thus secured in position to be operated upon by the travelling winder-tending mechanism, and is trimmed off to a definite length without requiring any attention on the part of the operative. At the proper time in the cycle of operations of the winder-tending mechanism, the part E (Fig. 2) travels into engagement with the arm 29 and opens the clamp, whereby the reserve thread is released to be disposed of by the winder-tending mechanism, and the clamp is restored to position to receive another thread.

When the shearing blade 15 needs to be sharpened or replaced, it may be readily sprung off the pivot 19 and withdrawn from the clip 22. The parts of the shear and clamp herein disclosed may be readily assembled and disassembled.

It will be seen that upon removal of the cover 7 and disengagement of the spring 34 from the lug 35, the three-arm lever 25 and the gear segment 26 may be slipped off the pivot 31, and the shear and clamp proper may be removed by springing the clip 17 until the head of the rivet 19 is out of the opening 21 and then slipping the shear and clamp to the right (Fig. 7) until the clip 17 is free of the housing.

While I have described the present embodiment of the invention with considerable particularity, it will be understood that various changes may be made in the arrangement and construction of the various parts without departing from the spirit and scope of the invention as defined in the appended claims.

I claim as my invention:

1. The combination of a housing having a slot and a throatway leading to the slot, a clamping jaw and a shearing blade within the housing at one side of the slot, an intermediate clamping and shearing jaw pivoted within the housing to swing across the

slot, said jaw having a gear segment connected thereto, a three-arm lever pivoted within the housing, a gear segment connected to said lever and meshing with the 5 first gear segment, said lever comprising an arm extending across the slot in the path of an entering thread, and an oppositely extending arm projecting from the housing, said lever also comprising a third arm, a link connected to the third arm, and a contractile spring connected to the link, said lever being arranged to be thrown slightly over center to a position where the spring 10 serves to hold the intermediate jaw in open position.

2. The combination of a housing having a slot and a throatway leading to the slot, a jaw located at one side of the slot within the housing, a second jaw arranged to swing 20 across the slot, a spring tending to swing the second jaw into engagement with the first jaw, and a member extending across the slot in the path of an entering thread for controlling said spring.

25 3. A combination clamp and shear consisting of a clamping jaw, a shearing blade, and a combination clamping and shearing jaw pivoted between the clamping jaw and the shearing blade, means for detachably securing the shearing blade in place, and a clip connected to the clamping jaw adapted to secure the whole to a suitable support.

4. In combination, a combined clamp and shear, a spring for actuating the same, and a member to control the spring, said member being in position to be moved by a thread which is being drawn into the clamp and shear.

40 5. The combination of a clamp, a spring for actuating the clamp, and a member to control the spring, said member being in position to be moved by a thread which is being drawn into the clamp.

6. The combination of a shear, a spring

for actuating the shear, and a member to 45 control the spring, said member being in position to be moved by a thread which is being drawn into the shear.

7. The combination of a clamp, a lever for operating the clamp, said lever comprising two oppositely-extending arms, one for closing the clamp and the other for opening the clamp, the first mentioned arm lying in the path of a thread which is being placed in the clamp. 55

8. The combination of a shear, a lever for operating the shear, said lever comprising two oppositely-extending arms, one for closing the shear and the other for opening the shear, the first mentioned arm lying in the 60 path of a thread which is being placed in the shear.

9. The combination of a clamp, a lever for operating the clamp, and a spring for swinging the lever to close the clamp, said 65 lever comprising an arm by means of which the lever may be swung slightly over center to a position wherein the clamp is held open by the spring.

10. The combination of a shear, a lever 70 for operating the shear, and a spring for swinging the lever to close the shear, said lever comprising an arm by means of which the lever may be swung slightly over center to a position wherein the shear is held open 75 by the spring.

11. A winder having a thread clamp arranged to be closed by the pressure of a thread inserted into the clamp.

12. A winder having a shear arranged to 80 be controlled by the pressure of a thread inserted into the shear.

13. A winder having a spring-actuated combined clamp and shear arranged to be controlled by the pressure of a thread. 85

In testimony whereof, I have hereunto affixed my signature.

HOWARD D. COLMAN.
